REPEATING FIREARM

Val A. Browning, Ogden, Utah, assignor to J. M. &
M. S. Browning Company, Ogden, Utah, a corporation of Utah

Application July 9, 1941, Serial No. 401,602

2 Claims. (Cl. 42—16)

1

This invention relates to repeating firearms and finds particular application in a firearm of the blow-back type wherein the expanding power gases are utilized to automatically perform the functions of retracting the breech block and withdrawing the spent case, it being understood, however, that certain of the improvements may be used in other types of guns.

The aim of the invention is to provide a repeating firearm which has various features of novelty and advantage and which is particularly characterized by its lightness in weight so that it may be easily carried and readily and quickly brought to firing position; which is very simple in construction and economical in manufacture, the various mechanisms and parts being of simplified construction conducive to low cost of manufacture and ready assembly and repair; which is very effective, reliable, and smooth in operation in that it may be accurately aimed and fired, the arrangement being such that during firing the gun may be held on the target without appreciable tendency to jump or weave and the shock caused by recoil is distributed or smoothed out so as to relieve the shoulder of the shooter from excessive jars and relieve the firing and other mechanisms of the firearm from excessive strains or stresses, thus insuring to the gun a long and useful life; and which may be conveniently fired in either a semi-automatic or full automatic manner at the immediate selection of the shooter; in short, to provide a better firearm which is of minimum weight, more economical in construction and manufacture, more effective and convenient in operation, and which is particularly adaptable for military use.

A further aim of the invention is to provide certain improvements in the several mechanisms with which the gun is provided.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the accompanying drawings:

Figure 1 is a side elevational view of my improved firearm;

Fig. 2 is a sectional view taken generally longitudinally and vertically through the receiver of the firearm and showing the various parts in their normal or firing positions;

Fig. 2A is a detail view showing a portion of

the magazine box in horizontal section, the rear end of the follower in top elevation, and the arm 166 of the stop-open latch in broken lines;

Fig. 3 is a sectional view taken generally longitudinally and vertically through the forward end of the stock and the tube or housing for the recoil spring, the rear end of the receiver being shown in elevation;

Fig. 4 is a detail view, partly in section, of the means for locking the receiver to the tube which houses the recoil spring;

Fig. 5 is an elevational view of said locking means;

Fig. 6 is a transverse sectional view through the stock, the rear sight being shown in front elevation, this view being taken on line 6—6 of Fig. 3 looking rearwardly in the direction of the arrows;

Fig. 7 is a transverse sectional view through the receiver and shows the magazine latch in front elevation, this view being taken substantially on line 7—7 of Fig. 2 looking rearwardly in the direction of the arrows, the magazine being omitted;

Fig. 8 is a transverse sectional view through the receiver in the plane which includes the pivot for the trigger, this view being taken substantially on line 8—8 of Fig. 2 looking rearwardly in the direction of the arrows;

Fig. 9 is a transverse section through the rear end of the receiver, this view being taken substantially on line 9—9 of Fig. 2 looking forwardly in the direction of the arrows, the sear 42 and the spring 125 being omitted in the interest of clarity;

Fig. 10 is a longitudinal vertical sectional view through the rearward end of the receiver looking towards the right hand side of the firearm with the parts of the firing mechanism shown in normal or firing position and with the screw 103 so adjusted that the gun can be fired in a semi-automatic manner only;

Fig. 11 is a view similar to Fig. 10 but showing the parts in fired position, the trigger being shown as having been pulled and the breech block and firing pin being illustrated in substantially their rearmost positions;

Fig. 12 is a view similar to Figs. 10 and 11 but showing the parts in the positions which they have when the trigger is maintained in pulled position after firing and the breech block and firing pin have returned to their normal firing positions;

Fig. 13 is a view similar to Fig. 11, the screw 103

having been backed off and the trigger being held in a position to effect full automatic firing;

Fig. 14 is a view similar to Fig. 13 and shows the manner in which the connector cams the sear to a release position when the recoil mass moves to its forward position while the trigger is maintained pulled to effect full automatic firing;

Fig. 15 is a side elevational view of the stock with its butt end in section in order to illustrate the manner in which the butt loop sling may be adjusted; and

Fig. 16 is a view showing the breech block, the extension block and the trigger plate in perspective.

Referring more in detail to the drawings, 15 wherein I have shown, for illustrative purposes, one embodiment which the present invention may take, A designates generally a receiver; B, a barrel secured in any suitable manner to the forward end of the receiver; C, a stock which may be of the usual construction; D, a tube or sleeve for housing the recoil spring E, this sleeve being mounted in the forward end of the stock and having its forward end demountably connected to the rear end of the receiver; F, the breech block forming a part of the multi-part recoil mass mounted in the receiver; G, a cartridge magazine of the usual construction; and H, the trigger plate located within the receiver and supporting the trigger mechanism, the magazine latch, and the stop-open latch, as described more in detail hereinafter.

The receiver A is preferably in the form of a cylindrical tube, this making for lightness in weight and cheapness in construction. As shown in Fig. 2, the forward end of the cylindrical receiver is internally threaded as at 10 so as to receive the rear threaded end of the barrel B which may be of the usual construction. The rear end of the cylindrical receiver is externally threaded as at 11 so as to be demountably screwed into the internally threaded enlarged forward end 12 of the recoil spring tube D. The receiver, adjacent its forward end and on its under side, is longitudinally slotted as at 13 to provide a loading opening which accommodates the upper end of a replaceable magazine G which may be of the usual sort. Secured to the forward end of the receiver, as by means of a screw 14, is a wooden holder 15 of generally U shape in cross section so as to receive the magazine. Secured to the holder, as by means of a screw 16, is a rectangular shaped band or guide 17 into which the magazine is adapted to be slipped to the position shown in Fig. 2. The receiver, adjacent its forward end and on its right hand side, has an ejection opening 18 through which the spent case is thrown upon recoil of the breech block in the usual manner. The receiver at its rear end and on its underside has a slot 19 for accommodating the trigger 41.

The casing D for housing the recoil spring E and for guiding parts of the recoil mass on its recoil and forward movements is also preferably in the form of a cylindrical tube in the interests of lightness in weight and economy in manufacture. This tube is in axial alignment with the receiver and barrel and is mounted within a bore 24 in the forward end of the stock C. The bore may be open at the upper side of the gun as at 25. The stock may be provided at its forward end with a depending pistol grip 23. Screwed into the rear end of the tube D is a threaded plug 27 (see Fig. 3). Within the tube and forwardly of the plug is a buffer in the form of a fibre disk 28 against

which the rearward movement of the recoil mass is arrested when the firearm is fired. This mass, as hereinafter described more in detail, includes, in the present illustrative disclosure, the breech block F, an extension block 29, and a follower block 30. The tube D is secured within the bore 24 of the stock by a screw 32, the forward end of which is screwed into a central opening in the plug 27. The head of the screw abuts against a rearwardly facing shoulder 33 on the stock. This screw 32 is in axial alignment with the tube D and the receiver A and it is hollow or bored out so as to accommodate the rear end of the stem of the firing pin 34.

The trigger plate H is secured as by means of a screw 40 within the cylindrical receiver A, rearwardly of the loading opening 13. This trigger plate supports the firing mechanism which includes a trigger 41, a sear 42, and a connector 43. The trigger plate further supports at its forward end an ejector 44, a magazine latch 45, and a latch 46 (herein referred to as a stop-open latch) for automatically latching the breech block in its retracted position after the last shot in the magazine has been fired or for manually latching the breech block in its retracted position at will. This trigger plate, as will be seen from Fig. 8, is a parti-cylindrical member with its under surface conforming to and seating snugly against the internal periphery of the receiver rearwardly of the loading opening. The upper surface of the plate to opposite sides of the center line thereof is flat and smooth so as to provide lands 52 (see Figs. 7, 8 and 16) which 25 slidably support the breech block F and the extension block 29 of the recoil mass during the recoil and forward movements of such mass. The plate at its rear end is longitudinally slotted as at 47 so as to accommodate the trigger mechanism, and the plate at its forward end is slotted as at 48 to accommodate the latches 45 and 46. As stated, the trigger plate is secured against the bottom portion of the receiver by the screw 40 and this screw is also employed to hold a trigger guard 49 in place. Also, for accurately positioning the trigger plate in the receiver and holding it against movement relative thereto the trigger plate has two laterally spaced apart depending dowels 50 which closely take into correspondingly positioned holes in the receiver (see Figs. 7 and 16).

Referring now to the recoil mass, the same, as stated, includes two or more parts arranged in succession and mounted one behind the other, these parts having a limited relative movement in the direction of the axis of the gun upon firing in order to disintegrate the shock of recoil as hereinafter described more in detail. In the present instance, this recoil mass comprises the breech block F, the extension block 29, and the follower block 30. The breech block consists of a parti-cylindrical member slidably fitting within the receiver above the trigger plate. The trigger plate and breech block are complementary to one another, that is to say, in cross section they form a cylinder which is divided along a common chord (see Figs. 2, 7 and 16). The under side of the breech block is longitudinally grooved as at 55 to each side of its center and has laterally beyond these grooves flat surfaces 56 which engage the lands 52 of the trigger plate. The upper wall 69 of the left hand groove 55 serves as a connector holding surface. The breech block has a central or axial bore 57 which slidably receives the firing pin 34 which has on its for-

ward end a firing point 58. The bore 57 stops short of the forward end of the breech block so as to provide an end wall 57' which has a small opening 59 axially aligned with the bore for accommodating the firing point 58 when the firing pin is in forward position with respect to the breech block. The under wall of the bore is longitudinally slotted as at 60 so as to accommodate the ejector 44 which may be of the usual construction and which, as previously stated, is carried by the forward end of the trigger plate H. Mounted in the forward end of the breech block is an extractor 61 for withdrawing the spent case from the firing chamber of the barrel upon recoil of the breech block when the gun is fired. This extractor may be of any ordinary kind, the same being diagrammatically shown in the drawings.

The extension block 29 comprises a generally cylindrical piece (see Figs. 2 and 16), the body portion of which is of the same general radius as the internal radius of the tube D so that it may slidably fit in said tube. The forward end of the extension block has an enlarged head 62 of substantially the same radius as the breech block and this head slidably fits within the cylindrical bore of the receiver. The under side of the extension block up to just short of its rear end is slabbed off so as to provide surfaces 63 which ride upon the lands 52 provided on the upper surface of the trigger plate. The rear end of the extension block is in the form of a substantially complete cylinder which fits in and is always engaged within the tube D. This extension block has an axial bore 64 aligned with the bore 57 of the breech block for accommodating the firing pin. This bore is open at its under side, as shown most clearly in Figs. 8 and 9, so as to accommodate the rear end of the sear during longitudinal movement of the extension block and to permit the sear to engage in the notch 65 of the firing pin for holding the firing pin in cocked position. It may be stated here that this notch at its rear end has a shoulder 66 against which the rear end of the sear is adapted to engage. The notch at its forward end is tapered as at 67. The extension block has on its under side and to the left hand side of the bore 64 a connector holding surface 68 which is above the plane of the surfaces 63. This surface 68 is in the same plane as and, in effect, forms a continuation of the surface 69 which defines the upper wall of the left hand groove 55 in the under side of the breech block F. At the rear end of this connector holding surface 68 is a notch 70 which opens into the left hand side of the extension block. The rear wall 71 of this notch is abrupt or perpendicular and its front wall 72 is forwardly and downwardly inclined for a purpose to be later described.

The follower block 30, which is located within the tube D, is in the form of a piston having its forward end of such diameter as to slide within and be guided by the tube. The rear end of this block is of somewhat reduced diameter so that the forward end of the recoil spring E may surround the same and abut against the shoulder provided by the rear end of the forward enlarged portion. This block also has an axial bore 74 in line with the central bores of the breech block and extension block so that these several bores may accommodate the firing pin.

In the present illustrative disclosure, the breech block F and extension block 29 are connected together so that the relative movement

therebetween in an axial direction is somewhat limited, one purpose of this arrangement being to prevent such separation of the blocks on firing of the gun as would permit the connector 43 from being caught or jammed in the gap between the extension block and the breech block during movements of those blocks. This connection between the blocks may in some instances not be required. In the present instance, the connection, as will be seen from Figs. 2 and 11, is in the form of a pin and slot arrangement comprising a transverse pin 75 carried by the rear end of the breech block and bridging a notch therein and a slot 76 provided in a tongue 77 projecting from the forward end of the extension block into said notch. For a purpose to be later described, I provide between the breech block F and the extension block 29 means which normally tends to urge these two blocks apart. In the present instance, this means includes a coiled compression spring 78 located in a longitudinally extending hole in the rear end of the breech block and bearing at its rear end against the forward end of the tongue 77.

The firing pin 34 is provided with a rearwardly extending rod or stem 90 for supporting a firing pin spring 91 coiled thereabout (see Fig. 3). This spring, at its forward end, abuts against the rear end of the body portion of the firing pin and at its rear end abuts against a disk 92 through which the rear end of the stem 90 slidably extends. The rear end of the stem is headed or peened over as at 93 so that the disk cannot come loose from the stem. This disk abuts against the forward end of the hollow screw 32. It is clear that the rear end of the firing pin extends into the screw when the firing pin is in other than full advanced or fired position.

By providing a multi-part recoil mass of the character just described, the shock caused by recoil to the shoulder of the shooter and to the firing and other mechanisms of the firearm is reduced or disintegrated, as will be clearly understood from the following explanation. When the parts are in their forward firing positions shown in Fig. 2, the breech block F is forced against the rear end of the barrel, and the breech block, extension block 29 and follower block 30 are forced together by the recoil spring E so that the three blocks act as an integral mass to close the breech. As a result, at the instant a cartridge in the firing chamber is fired, the power gases generated act upon the various blocks as though they were one integral mass, the recoil mass being driven violently to the rear causing compression of the recoil spring. However, upon such rearward movement, the breech block lags behind the follower block so that the blocks separate slightly with the result that the recoil movements of the follower block, the extension block, and the breech block are successively stopped in that order at very slight intervals apart so that the shock of stopping such rearward movements is disintegrated or smoothed out. More particularly, it will be seen that lagging of the breech block upon recoil with respect to the extension block is due to the spring pressure of the firing pin spring 91 (the forward end of the firing pin being against the end wall 57' of the breech block) and also due to the friction of the uppermost cartridge in the magazine against the bottom of the breech block. As the breech block's rearward velocity is thus retarded, the breech block and extension block separate slightly, the extent of separation being limited by the pin and slot con-

nection 75 and 76. This separation is further aided by the spring 78 which is interposed between the extension block and the breech block. After a separation between the breech block and the extension block to the extent allowed by the pin and slot connection, the extension block will move rearwardly at the same rate as the breech block and thus the rearward movement of the extension block will lag with respect to the follower block, thus permitting the follower block to separate slightly from the extension block. Rearward travel of the follower block is limited by the impingement of that block against the buffer 28 located in the rear end of the recoil spring tube D; the extension block then stops against the forward end of the follower block, and then the breech block stops against the forward end of the follower block. Thus the several blocks of the recoil mass are separately and successively stopped in their rearward movements, these stoppages being effected in an almost imperceptible period of time but they being spaced apart sufficiently in time to permit of a smoothing out or distribution of the shock of recoil over that which would result should such movement between the several parts not be permitted. Thus the jars to which the shoulder of the shooter is subjected are somewhat relieved, and the strains and stresses caused by shock upon recoil upon the various parts and mechanisms of the gun are reduced. The spring 78 also serves the purpose of aiding in disintegrating or distributing the shock incident to stopping the forward movement of the recoil mass. It is understood that the recoil spring is compressed during recoil and then that spring forces the recoil mass forwardly into the firing positions shown in Fig. 2. During such forward movement, the spring 78 accelerates the forward speed of the breech block relative to the other blocks so that the breech block stops against the rear end of the barrel and then the extension block will stop against the rear end of the previously stopped breech block.

It will further be observed, particularly from Figs. 1, 2, and 3, that the barrel, tubular receiver, and the recoil spring tube are in a straight line alignment, that is to say, their axes coincide; and that the buffer 28 in the rear end of the recoil spring tube D against which the recoil mass impinges on firing of the gun is positioned an appreciable distance rearwardly from the forward end of the stock and more closely to the shoulder of the shooter than has heretofore been the case, and thus, upon recoil, the shock of the recoiling parts is in the line of fire and is closely adjacent to the butt end of the stock which engages the shoulder of the shooter. This is all of advantage in that tendency for the gun to jump or weave upon firing is greatly reduced and the firearm may be more readily aimed and more readily held on the target. It will further be observed that the receiver and the recoil spring tube are cylindrical members so that they can be readily and economically manufactured either by simple drawing or turning operations and that these parts are of relatively light weight while at the same time they have sufficient strength to adequately perform their functions.

The firing mechanism, which includes the trigger 41, the sear 42, and the connector 43 will now be described. The trigger is pivoted on a pin 100 located adjacent the forward end of the slot 47 in the trigger plate. Also pivoted on this pin and between the ears on the forward end of

the trigger is a pressure lever 101 the under side of the forward end of which is adapted to abut against a shoulder 102 on the trigger plate for the purpose of limiting the extent of upward pull on the trigger. Preferably, in order to prevent cramping between the trigger and the pressure lever, a bearing sleeve 99 (see Fig. 8) is interposed between the pin 100 and the trigger, and the pressure lever is journaled on this sleeve. This lever 101, as hereinafter described more in detail, is held against pivotal movement relative to the trigger when the gun is to be fired only in a semi-automatic manner by a screw 103 mounted for axial adjustment in a threaded opening in the body of the trigger. About this screw and between the tail end of the lever and the trigger is a coiled spring 104 the purpose of which will be hereinafter described more in detail. Downward movement of the trigger is limited by the engagement of a small rearwardly extending lug 105 against the bottom portion of the receiver, as shown most clearly in Fig. 2.

The sear 42 is pivoted between its ends on a pin 106 carried by the trigger plate rearwardly of the pin 100. The rear end of this sear has a shoulder 107 adapted to engage the shoulder 66 of the firing pin for holding that pin in the firing position shown in Figs. 2 and 10. The forward end of the sear has a downwardly facing connector engaging face 108 which terminates at its rear end in a connector locking abutment 109 disposed generally at right angles to the face 108. The sear further has, rearwardly of the abutment 109 and meeting the upper end of that abutment at an obtuse angle, a cam surface 110. The extreme forward end of the sear also has a rearwardly facing depending hook 111 which is adapted to interlock with the connector 43 in order to prevent the sear from being jarred from firing pin holding position.

The connector 43 is pivoted to the trigger as at 115. This connector has a sear engaging portion located beneath and in the vertical plane of the forward end of the sear, and this portion has a normally upwardly facing sear actuating surface 116 which is positioned beneath and in opposition to the connector engaging surface 108 of the sear when the firing mechanism is in the normal or firing position shown in Figs. 2 and 10. At the forward end of the surface 116 is a forwardly extending lug 117 which is adapted to take into the hook 111 (see Figs. 2 and 10). The forward end of this lug constitutes an abutment at the forward end of the surface 116 and this abutment is adapted to engage the connector locking abutment 109 of the sear as shown in Fig. 12 for the purpose of preventing the connector from swinging forwardly to a position where the surfaces 108 and 116 are opposed until the trigger is released after the trigger has been pulled and the gun has been fired in a semi-automatic manner. The upper forward corner 119 of the sear engaging portion of the connector, that is, the corner between the surface 116 and the abutment formed by the forward surface of the lug 117 is adapted to engage the cam surface 110 of the sear so as to automatically release the sear from the firing pin when the firearm is being fired in a full automatic manner. Extending upwardly from the sear engaging portion of the connector and located to one side of the sear is a finger 118 which extends into the notch 70 of the extension block when the recoil mass is in its forward position (see Figs. 9 and 10). The upper end of the finger is in engagement with the connector engaging surfaces 68 and 69 of the

extension block and follower block during the rearward and forward movements of such blocks (see Figs. 11 and 13).

The sear is normally urged into its firing pin holding position, the trigger is normally urged towards its unpulled position, and the connector is normally urged forwardly into a sear actuating position by a very economical, simple, and effective spring arrangement which may be easily and quickly installed. These functions are obtained by a single spring 125 which is preferably in the form of a round spring wire bent generally into S form. The sear is longitudinally grooved on its under side so as to provide a kerf which accommodates the upper arm of the spring with the upper bend or crook of the spring in partial encircling relation to the pin 106 on which the sear is pivoted. The forward end of the lower arm of the spring is received by a hole in a projection 126 extending forwardly from the base of the finger 118 of the connector. Extending through the bottom crook or bend of the spring is a transverse pin 127 removably carried by the trigger plate. To install the spring, it is merely necessary to slip the upper arm thereof into the sear, slip the forward end of the lower arm into the hole in the projection 126, and then slip the pin 127 into the bottom crook of the spring.

As previously stated, when the screw 103 carried by the trigger is screwed home so that the pressure lever 101 can have no relative movement with respect to the trigger, the gun can be fired only in a semi-automatic manner. Assuming, for the present, that that condition exists, the functioning of the mechanism is briefly as follows. Figs. 2 and 10 shows the firing mechanism in its normal position, that is, the breech is closed and the gun is ready for firing. It will be observed that the sear is in cocked position, the trigger is down in unpulled position, and the connector is in its forward position with its sear engaging surface 116 opposed to the downwardly facing surface 108 on the forward end of the sear and with its finger extending into the notch 10 of the extension block. Upon pulling of the trigger, the connector is raised resulting in actuation of the sear and release of the firing pin. The firing pin, under the compression of the firing pin spring 91, moves sharply forward so that this pin strikes the primer of the cartridge located within the firing chamber of the barrel. On the resulting explosion, the power gases drive the recoil mass backwardly, as previously described, and as this mass starts backwardly, the inclined camming surface 72 on the extension block engages the finger 118 of the connector and cams the connector to the position shown in Fig. 11 and in which position it is thereafter held by the connector engaging surfaces 68 and 69 of the extension block and breech block during the rearward and forward movements of those blocks providing that the trigger is held in the pulled position shown in Fig. 11. Upon the return of the recoil mass to its forward position, the trigger still being maintained in pulled position, the connector and sear assume the positions shown in Fig. 12. As therein shown, the sear is in cocked or firing pin holding position but the connector is held from moving forwardly to its full forward position by the engagement of the connector against the abutment 109 on the sear. In other words, the connector is maintained by the sear from moving to its normal position in which the face 116 of the connector is beneath the face 108 of the sear. This means that in order to again fire

the gun, the trigger must be released and again pulled between which movements the connector would be released from the sear bringing the face 116 of the connector beneath the face 108 of the sear. Of course, if, during the movement of the recoil mass, the trigger is released, the parts automatically assume the positions shown in Fig. 10 when the recoil mass reaches to its forward or normal breech closing position. It will be observed that when the gun is set to operate in a semi-automatic manner, the extent to which the trigger can be raised is limited to the position shown in Figs. 11 and 12 and in which position the camming corner 119 on the connector is not high enough to engage the camming surface 110 of the sear.

When it is desired to adapt the firearm so that it may be selectively operated in either a semi-automatic manner or a full automatic manner by varying the pull of the operator's finger on the trigger, the screw 103 is backed off, as shown in Figs. 13 and 14, to permit of a pivotal movement of the trigger with respect to the pressure lever 101. This allows the trigger to be selectively moved to the position shown in Figs. 11 and 12 in which semi-automatic firing is obtained, or to the higher position (by exerting a greater pull on the trigger) shown in Figs. 13 and 14 in which full automatic firing is obtained so long as the trigger is maintained in its fully pulled or highest position. Assuming that the screw 103 has been backed off, the operation of the firing mechanism is now briefly as follows. Starting with the parts in their normal firing positions shown in Fig. 2, if it is desired to fire the firearm in a semi-automatic manner, the trigger is pulled to the intermediate position shown in Figs. 11 and 12 and in which position, it being assumed that the screw 103 has been backed off, the coiled spring 104 is not compressed or at least is not compressed to any appreciable extent. The operation will now be the same as that previously described in connection with the semi-automatic firing. If it is desired to fire in a full automatic manner, it is merely necessary to exert a harder pull on the trigger thus raising the trigger to its upper limit of movement shown in Figs. 13 and 14, it being observed that, due to this harder pull, the spring 104 is compressed. Upon upward movement of the trigger from its unpulled position shown in Fig. 2, the connector will release the sear from the firing pin in the same manner as heretofore described, resulting in the first firing of the gun. Upon recoil of the recoil mass, the cam surface 72 of the extension block will cam the connector backwardly to the position shown in Fig. 13 in which position it will be held by the connector engaging surfaces 68 and 69 of the extension block and breech block during the rearward and forward movements of those blocks. It will be observed that the connector has a more rearward position than that shown in Fig. 11 because the pivot 115 for the connector is in a higher position during full automatic firing than it has during semi-automatic firing. During forward movement of the recoil mass, the rear end 107 of the sear will automatically engage the shoulder 68 of the advancing firing pin and thereby hold the firing pin in cocked position until the recoil mass reaches its breech closing position. As the recoil mass approaches such position, the vertical wall 71 of the notch 10 will engage the finger 118 and positively swing the connector forwardly so that the corner 119 on the body portion of the connector will engage

and ride along the cam surface 110 of the sear, thus camming the forward end of the sear upwardly and the rear end downwardly with the result that when the recoil mass has fully reached its breech closing position the firing pin is automatically released and the firearm is fired a second time. The firearm will continue to fire in a full automatic manner so long as the trigger is held in its fully raised position and so long as cartridges are supplied to the gun. As long as the trigger remains in full pulled position, the upwardly facing shoulder 116 on the connector cannot come below the connector engaging surface 108 of the sear for each time that the connector is swung forwardly by the extension block, the forward face of the lug 117 forms a stop-face for engagement with the rearwardly facing abutment 109 of the sear. The perpendicular shoulder or wall 71 of the notch 70 of the extension block pushes the connector substantially to the last mentioned position but not beyond it. When it is desired to cease full automatic firing, it is merely necessary to release the trigger in which case the parts again assume the position shown in Fig. 2. It is thus noted that the operator may very quickly and readily change from firing in a semi-automatic manner to a full automatic manner and vice versa by merely changing, at any time he may desire, the amount of pressure which he exerts on the trigger.

It may be desirable at times to selectively render the firearm operable for either semi-automatic firing or for full automatic firing without employing the selective arrangement just described, and to this end I provide a manually adjustable sector which also serves the purpose of locking the trigger of the firing mechanism in "safety" or unpulled position. This manually adjustable selector comprises a split metal band 135 mounted for angular adjustment in a groove provided in the outside of the receiver adjacent the rear end thereof. The trigger, adjacent its rear end and behind the connector, is provided at opposite sides with two upwardly facing shoulders 138 and 139, the left hand shoulder being lower than the right hand one. The ends 138 and 139 of the band are spaced apart at the slot 49 in the receiver through which the trigger extends. The band is adjustably adjusted to three positions, it being resiliently held in each of these positions by the selective engagement of a small nib 140 carried by the band in notches 141 provided in the external periphery of the receiver (see Fig. 9). The band is provided with finger pieces 142 so that it may be more easily adjusted to its several positions. With this arrangement, when it is desired to fire the gun in a full automatic manner, the band is adjusted to the mid-position shown in Fig. 9, in which case both ends of the band are out of the path of movement of the trigger so that the trigger may be raised to the full automatic firing position shown in Figs. 13 and 14. When it is desired to fire the gun in a semi-automatic manner only, the band is adjusted counterclockwise with respect to Fig. 9 so that the left hand end 138 of the band overlies the shoulder 136 on the trigger. The trigger then can only be pulled to the intermediate position shown in Figs. 11 and 12. When it is desired to lock the trigger in safety position, the band is adjusted to its other extreme position in which case the right hand end (referring to Fig. 9) of the band lies immediately over the right hand shoulder 137 of the trigger. The trigger cannot now be lifted from its unpulled position. It has

been previously pointed out that the sear has a rearwardly facing depending hook 111, and the connector has a forwardly extending lug 117 adapted to engage in the hook when the trigger mechanism is in normal condition. The purpose of this interlocking arrangement is to prevent the sear from being jarred out of its cocked position resulting in an accidental discharge of the firearm in the event the same were dropped or jarred. Thus, when the trigger is locked in safety position by the band 135, the sear is locked by the hook 111 against accidental movement. However, the gun may be cocked while the safety is in the "on" position without doing any damage to the parts because, upon the first opening movement of the breech block, the inclined surface 72 on the extension block will swing the connector out of locking engagement with the sear.

The magazine latch and the stop-open latch will now be described. The magazine, as is usual, has a box or body portion 150 within which is a follower spring 151 bearing at its upper end against a follower 152 (see Fig. 2). The follower at its rear end, has a rearward extension 154 which extends into a slot in the filler piece 153 secured to the wall of the magazine box (see Fig. 2A). The magazine latch 45 and the stop-open latch 46 are pivoted at their upper ends on a pin 157 carried by the forward end of the trigger plate and bridging the slot 48 thereof. This pin also supports the ejector 44 which, as shown in Figs. 2 and 7, is interposed between the upper ends of the two latches 45 and 46. The rear end of the ejector is engaged with the trigger plate as at 158 and with a stop pin 159 so that it is maintained against turning. The magazine latch has, at its lower end, a hook 160 which is adapted to engage a shoulder 161 provided in the rear wall of the magazine body whereby to hold the magazine in place. Extending rearwardly from the lower end of the magazine latch is a finger piece 162 whereby the latch may be manually withdrawn from magazine holding position. The stop-open latch is mounted for swinging movement with, and also for up and down movement relative to, the magazine latch. To these ends, the stop-open latch, adjacent its upper end, has an elongated slot 163 which receives the pivot pin 157, and the stop-open latch intermediate its ends carries a screw 164 provided with a reduced end which engages in an elongated vertical slot 165 in the magazine latch. The stop-open latch has at its upper end a forwardly extending arm 166, the under surface of which is adapted to be engaged by the rearward extension 154 of the follower when the last cartridge in the magazine has been removed therefrom. This arm, at its upper side, has a rearwardly facing stop or shoulder 167 located beneath the surface 69 which constitutes the upper wall of the left hand groove 55 in the breech block. When the stop-open latch is in its operative holding position, the forward end of the breech block engages this stop 167. The stop-open latch 46 at its lower end has a finger piece 168. The magazine latch is forced into the latching position shown in Fig. 2 by a strong helical spring 169 and a plunger 170 positioned in a bore in the forward end of the trigger plate. When the magazine with cartridges therein is inserted in the firearm, the cartridges are held by the filler piece 153 far enough forward so as not to interfere with the stop-open latch. However, after the last cartridge in the magazine has been fed by the advancing breech

block to the firing chamber, the rearward extension 154 of the follower 152 engages the under side of the arm 166 of the stop-open latch so that the follower spring 151 urges the stop 167 against the surface 69 of the breech block. Upon firing of the last cartridge, the breech block will recoil and the follower spring 151 will raise the stop-open latch 46 so as to position the stop 167 thereof in front of the forward end of the breech block. As the breech block strikes the stop-open latch, the latter swings slightly on its pivot and as the magazine latch is connected to the stop open latch by the screw 164, the latter latch swings rearwardly out of engagement with the magazine. Thus, after the last cartridge is fired, the breech block is automatically stopped in its open position and the empty magazine is automatically released from the firearm. It will be noted that when the breech block thus strikes the stop 167 of the stop-open latch, the comparatively stiff helical spring 169 is compressed and thus the stopping of the forward movement of the breech block is cushioned. To reload the firearm, a full magazine is placed in position and the stop open latch is manually moved downwardly whereupon the breech block moves forwardly taking the uppermost cartridge out of the magazine and moving it into the firing chamber ready for firing.

If it is desired to manually move the breech block to retracted position and lock the same in that position for the purpose of cleaning or examining the inside of the receiver or for any other reason, this may be done by manually retracting the breech block by means of a handle 175 and then manually raising the stop-open latch. The handle 175 projects from the right hand side of the breech block, as shown in Fig. 7. It will be observed that the magazine latch and stop-open latch are relatively simple in construction and the parts may be economically manufactured and assembled. Each of the latches comprises but one part. These two parts are pivoted on the same pin and are so connected that cushioning of the force of the recoil mass when stopped in open position is effected through the magazine latch bearing against the plunger 170 behind which is the spring 169.

As previously stated, the rear end of the receiver is adapted to be screwed into the forward end of the tube D. For the purpose of locking these parts against relative rotary movement, an improved take-down latch is provided. This latch, as shown most clearly in Figs. 4 and 5, comprises a slide having a stem 180 provided at its inner end with a locking head 181 and at its outer end with an elongated finger piece 182. The stem 180 extends through and is slidably mounted in an elongated slot 183 in the enlarged forward end 12 of the tube D. The rear end of the receiver is provided with a notch 184 which is adapted to receive the head 181 when the latch is in locking position. The latch is held in its two positions of adjustment by a leaf spring 185 positioned between the finger piece 182 and the head 12 of the tube D. This spring normally has a longitudinal curvature so that when it is positioned in place it will bear at its central portion against the under side of the finger piece 182 and at its ends against the periphery of the head 12. In order to permit the parts to be assembled, the spring has a transverse elongated opening 186 through which the finger piece may be inserted when the spring is in a position at 90° to that shown in Fig. 5. After the spring is thus slipped

over the finger piece, the spring is turned 90° to the position shown in that figure. In order to prevent the spring from turning out of the position shown in Fig. 5, the forward end of the spring has a finger 187 engaging in a groove 188 in the head 12. It will be seen that this take-down latch is very simple in construction and that the parts thereof may be readily assembled. The latch may be easily operated by sliding the finger piece from one position to another. The spring, in addition to serving to hold the latch in place, covers the slot 183 so as to prevent dirt or the weather gaining access to the interior of the receiver.

In order that the gun may be conveniently carried and quickly brought to shoulder position for firing, there is provided at the rear end of the stock C a butt-loop sling 190 (see Figs. 1 and 15). This sling is in the form of a strap, the respective ends of which are threaded through vertical slots 191 in the upper and lower walls of the stock adjacent its butt end. The ends of the strap within the stock may be adjustably secured together by a suitable buckle 192 located within a cavity in the stock. When carrying the firearm, the sling goes over the shoulder of the shooter with the gun depending along the side of the body and the leg of the shooter. When it is desired to fire the gun, all that is necessary is for the operator to grasp the handles thereof and swing the gun to firing position. During such movement, the sling slips about the shoulder of the shooter as a pivot.

Also, in accordance with the present invention, I provide an improved rear sight which is shown most clearly in Figs. 3 and 6. This sight includes a base block 195 located at the rear end of the slot 25 of the stock and secured, as by means of a screw 196, to the tube D adjacent the rear end thereof. The block has a forwardly facing shoulder 197 at each side, and forwardly of these shoulders is a transverse hole in which is located a pivot pin 198. On the opposite projecting ends of this pin are posts 199. The openings in the posts which receive the pin 198 are of larger diameter than the pin so that the posts may have a limited transverse movement. The posts support a sightpiece 200 which has a central circular portion 201 provided with a sight aperture 202. The central portion 201 is carried by side portions or arms 203 which are grooved on their opposing faces so as to provide guideways which accommodate the posts 199. One of the posts may be provided along its outer edge with notches 204 and one of the arms 203 may have a lug 205 adapted to selectively engage in these notches in order to hold the sightpiece in its several positions of adjustment depending upon the range at which the firearm is to be fired. For the purposes of urging the posts apart so that they will frictionally engage in the opposed surfaces provided by the guideways of the arms 203 and for resiliently holding the sight in the elevated position shown in Figs. 3 and 6 or in a down position where the sight lies horizontally within the groove 25, catches 206 and a spring 207 therebetween are provided. These catches and this spring are located in a transverse opening 208 in the base block 195 positioned upon and slightly forwardly of the pivot pin 198. The catches are preferably in the form of hollow caps having outer rounded ends so located that when the sight is in raised position the spring 207, acting through the caps, urges the posts 199 against the shoulders of the base block. When the sight is swung to folded or

down position, the catches engage the then upper edges of the posts so as to hold the sight in that position. In all positions of the sight, the posts are urged outwardly into frictional engagement with the sightpiece, and the sightpiece, acting through the posts, hold the catches within the transverse opening 208. It will be observed that, due to the loose mounting of the posts on their pivot 198, and due to the fact that the spring 207, acting through the catches 206, tends to urge the posts apart, the sightpiece may be adjusted on the posts by pressing the free ends of the posts towards each other, virtually adjusting the sightpiece to the desired position and then releasing the pressure on the posts; and the sightpiece is maintained in its adjusted position by the expanding apart of the posts.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language

used in the following claims is intended to cover all of the generic and specific features of the invention herein described and all statements of the scope of the invention which, as a matter of language, might be said to fall therebetween.

I claim as my invention:

1. In a firearm, a tubular receiver having a tubular bore, a parti-cylindrical trigger plate in the receiver having a flat upper surface and having its under surface curved correspondingly to and seating against the bottom of the receiver, a recoil mass having a parti-cylindrical breech block fitting within the bore of the receiver and having on its under side flat surfaces engaging the flat upper surface of said trigger plate, a spring behind said block and trigger mechanism carried by said trigger plate.
2. In a firearm, a tubular receiver of circular cross-section, a parti-cylindrical breech block guide fixedly mounted in said receiver, and a parti-cylindrical breech block arranged to rest and reciprocate on said guide, said breech block and guide fitting closely and complementarily into said tubular receiver.
